US00D615086S

(12) **United States Design Patent**
Morabito

(10) **Patent No.:** **US D615,086 S**
(45) **Date of Patent:** **** May 4, 2010**

(54) **ELECTRONIC DEVICE**

D606,036 S * 12/2009 Shimada ..... D14/138 G

(75) Inventor: **Pascal Ito Morabito**, Paris (FR)

(73) Assignee: **Deutsche Telekom AG** (DE)

FIG. 1 is a perspective view from top front side of an ornamental design for an electronic device;

FIG. 2 is a perspective view from bottom front side of the design shown in FIG. 1;

FIG. 3 is a front view of the design shown in FIG. 1;

FIG. 4 is a rear view of the design shown in FIG. 1;

FIG. 5 is a top side view of the design shown in FIG. 1;

FIG. 6 is a bottom side view of the design shown in FIG. 1;

FIG. 7 is a left side view of the design shown in FIG. 1; and,

FIG. 8 is a right side view of the design shown in FIG. 1.
